UNITED STATES PATENT OFFICE.

LINUS H. SHAW, OF BROCKTON, MASSACHUSETTS.

HEEL LIFT OR RAND.

1,146,288.

Specification of Letters Patent. Patented July 13, 1915.

Application filed January 21, 1915. Serial No. 3,473.

To all whom it may concern:

Be it known that I, LINUS H. SHAW, a citizen of the United States, and resident of Brockton, in the county of Plymouth and State of Massachusetts, have invented certain new and useful Improvements in Heel Lifts or Rands, of which the following is a specification.

The present invention relates to a heel lift, and its object is to provide a lift which may serve the purposes, either wholly or in part, of the rand which is ordinarily applied to that side of a heel which lies next to the bottom of the shoe to which the heel is applied.

Further objects of the invention and the advantages thereof, and the way the invention is carried into practice are set forth at length in the following description, in connection with the drawing which forms a part of the same.

In the drawing, Figure 1 is a plan view of a form of lift embodying my invention. Fig. 2 is a plan view of the lift showing the same in its distended condition. Fig. 3 is a longitudinal central section of the lift in the form shown in Fig. 1 and Fig. 4 is a similar section of the lift in the condition shown in Fig. 2. Fig. 5 is a plan view of a modification.

As a preliminary to describing the present invention I will briefly describe the conditions which have led to its development.

As is well known the bottom of a shoe is convex at the heel in order to fit the heel of the wearer's foot, and this convexity is very pronounced when the fit is a good one. Correspondingly, the face of the heel which comes next to the shoe bottom is made concave in order to fit the convexity of the shoe, and this concavity is called in the trade the "cup" of the heel. This cup is ordinarily produced in practice both by compressing the heel, with a greater pressure at the center than at the periphery, and by applying a rand to the edge of the heel, and sometimes by gouging out the central part of the heel in cases where an especially deep cup is required, or where it is desired to avoid the use of a rand. Various causes, which it is unnecessary to relate here, have made the supply of material suitable for rands insufficient for the demand, the result being that the price of good rand material has advanced to a high figure, which is prohibitive for many grades of shoes. Some manufac-

turers have attempted to avoid the use of rands and also to save the waste of material due to gouging out the cup of the heel, by confining the pressure used in compressing the heel practically to the central part thereof, leaving the peripheral part practically uncondensed. This procedure is objectionable in that it makes the central part of the heel too hard while causing cracks to open between the lifts on the outside of the heel, and it makes the heel wear unevenly. Others have attempted to meet the difficulty by making the heel with a very shallow cup and shaping the shoe bottom to fit the cup, the practice of which is objectionable because of spoiling the fit of the shoe, causing the weight of the wearer's heel to be concentrated on the center instead of being supported over the entire bottom of his heel, as it should be.

My invention is designed to provide an article which is partly a lift and partly a rand, which can be produced from stock unsuitable for rands of the usual construction, and which when applied to a heel enables the heel to be formed with a cup as deep as necessary, without either making the center of the heel too dense and the peripheral portions insufficiently dense or requiring part of the material to be cut away, as in gouging. In producing my invention I cut out of leather, leatherboard, or any other material which is sufficiently tough, flexible, and compressible, a piece *a* which may have the outline somewhat as shown in Fig. 1, which is generally that of a heel, but narrower than the heel for which the lift is intended, the length of the piece being approximately equal to the length, from breast to back, of the heel for which the piece is intended. This piece is partially divided, either in the operation of dieing, or subsequently, on a line which extends from the point *b* at the center of the breast edge of the piece, to a point *c* near the rear edge, so that the piece *a* is partially subdivided into two members which are integrally connected together by the material between the end *c* of the cut and the rear edge of the heel. This cut which divides the piece is zigzag between the points *d* and *e*, passing back and forth across the center line of the piece and forming interleaved tongues *f*, *f*, *f*, and *g*, *g*, *g* projecting from the respective sides or members of the piece. The line of the cut between the points *d* and *b* is straight

and near the middle line of the piece, and the stock on each side of this line is beveled from a thin edge *h* at the line to the full thickness of the piece near the outer edges 5 thereof.

The subdividing cut allows the members of the piece to be drawn apart, such members then bending at the narrow connecting tongue left at the rear, and also bending some- 10 what on the narrow parts between the periphery of the piece and the points of the zigzag cut. This allows the width between the outer edges of the piece to be made as great as that of the heel with which the piece is to be used, and the drawing apart of the tongues 15 *f* and *g* leaves open spaces in the central part of the heel, as is shown clearly in Fig. 2. The piece is locked in this distended or spread condition by the point of one of 20 the tongues *f* engaging a shoulder *i* on the side of the adjacent tongue *g*, and by the point of said tongue *g* engaging a shoulder *k* in the side of the next adjacent tongue *f*. These shoulders are formed by offsetting 25 the transverse lines of the cut at the proper points, the offsets being shown in Fig. 1 by the characteristic letters *i* and *k*, respectively.

More of the tongues than the two here 30 shown may be employed to lock the piece in its distended condition, or on the other hand one alone may be employed for the purpose. I find, however, that in practice two are sufficient for this purpose and also 35 that two are more efficient than one, and that the tongues which most efficiently perform the locking function are those which are here shown as employed for that purpose. The spreading apart of the sides of 40 the piece swings the points of the tongues forwardly, whereby they automatically slip into the notches and engage the shoulders provided as shown, and their natural stiffness retains them in locking engagement, 45 wherefore it is unnecessary when spreading open the piece to place the locking tongues in engagement with the coöperating shoulders, nor to take care that they remain in such engagement after the piece has been 50 spread open.

The piece is applied to the seating face of the heel in its distended condition. The open spaces left in the central part of the heel between the interleaved tongues gives 55 room for the spreading out laterally of the tongues in the crushing effect produced by the compressing operation. Thus a heel having one of these lifts on its seating face, when compressed between the dies ordinarily used for the purpose will have greater compressibility in the central part than at the periphery and may be so compressed as to form a deep cup without making the central part too dense and hard or leaving 60 the peripheral part too soft and insuffi-

ciently condensed. If an exceptionally deep cup is required a rand may be laid on the peripheral part of the lift *a*, or two such lifts may be employed without any rand.

Among the advantages derived from my 70 invention may be named the following.

(1) The lift or piece can be cut from a piece of leather or other material not sufficiently large either to furnish a complete heel lift or to furnish a rand of the proper 75 form. A rand of the sort heretofore used must have peripheral length as great as the entire periphery of the heel exclusive of the breast line, and when cut from a side of leather or sheet of other stock, is cut in as 80 nearly a straight strip as possible in order that it may be divided into two wedge shaped strips, each capable of being bent to the curvature of the heel. In cutting heel lifts from leather and other sheet material 85 many scraps are left from which it is impossible to make a strip long enough and straight enough to be used as a rand, or which are wide enough for a complete lift, and out of such scraps pieces of the sort 90 here shown may be made. It is not essential that the piece should have as great width as here illustrated, for it may be made narrower if desired and may be conformed to the heel by simply spreading its sides 95 somewhat more widely apart. The tongues in any case perform the function of holding the sides apart in essentially the manner shown.

(2) The use of my lift enables heels with 100 deep cups to be made without requiring gouging out of any of the material and thus saves the material which is wasted in the gouging operation.

(3) The heel containing my lift can be 105 compressed to form the cup without confining the pressure entirely or to an objectionable degree to the central part of the heel.

The particular form and arrangement of the dividing cut and of the tongues formed 110 thereby, herein illustrated, are shown merely for the purpose of illustration to represent an operative embodiment of the invention and are without limiting significance. A lift or piece cut with any outline and having 115 an intermediate dividing cut of any configuration, providing the outline permits the piece to be spread apart to the width of the heel, and the dividing cut forms locking members or braces to hold the sides in the 120 spread apart condition, is within the view of my invention. It will therefore be apparent that any configuration of the interleaved tongues which accomplishes the desired result of holding the sides of the lift 125 spread apart, whether by the positive action of an abrupt abutment or shoulder, or by friction, is within the scope of the invention. The tongues may be given any form and may be caused to extend in any direc- 130

tion desired, all within the scope of this invention, by appropriately modifying the outline of the dividing cut.

What I claim and desire to secure by Letters Patent is:

- 5 1. A heel lift comprising a piece narrower in width than the heel for which it is designed, and being sub-divided from its breast to a point near its rear edge on a line 10 which is laterally offset so as to form a brace and a part to coöperate therewith.
- 15 2. A heel lift or rand consisting of a piece having a peripheral form generally similar to that of a heel and an extent, exclusive of 20 the breast, equal to the peripheral extent, also exclusive of the breast, of the heel with which the lift is to be used, said lift having an intermediate cut extending from one end to a point near the opposite end, and off-set 25 between its ends to form a laterally extending brace and a complementary shoulder, adapted to permit the sides of the lift to be separated, and to hold them in separated position.
- 30 3. A heel lift or rand comprising a piece having a curved outline of less width than the heel for which it is designed and having an intermediate longitudinally extending cut dividing the piece into two side members which are integrally connected at the 35 rear end of the piece, said dividing cut being offset at an intermediate point so as to provide a lateral tongue extending from one of said side members into a corresponding recess in the other side member, and the cut being further locally offset to provide a shoulder at the side of said tongue away from the point at which said members are connected together.
- 40 4. A heel lift or rand comprising a piece having a curved outline divided into two side members connected together at the rear end of the piece, said side members being adapted to be spread apart and having alternate projections or tongues, and recesses, 45 the tongues of each side member being contained in the recesses of the opposite member, and one of the tongues having in its side a notch adapted to receive the point of the adjacent tongue on the opposite side 50 member, and forming a shoulder whereon said tongue may abut when the side members are spread apart.
5. A heel lift comprising a piece of less width than the heel in which it is designed 55 to be used, said piece being partially subdivided by a zigzag cut extending from the breast toward the rear end and so offset as to form interleaved tongues, adapted to be drawn apart and formed to coöperate in 60 holding the piece distended to a greater width than its original width.
6. A heel lift comprising a piece partially subdivided by a cut extending from the breast end to a point near the rear end and 65 being laterally offset to form a tongue on one of the subdivisions of the piece and a complementary socket in the other subdivision, said tongue and socket being so formed as to permit spreading apart of the 70 sides of the piece and engagement of the tongue with a part of the socket in such a manner as to hold the piece in the spread condition.

In testimony whereof I have affixed my 75 signature, in presence of two witnesses.
